RAILWAY CAR

David A. Crawford, Golf, Alexander E. McKinnon, Homewood, and Carl H. Apel, Chicago, Ill., assignors to The Pullman Company, Chicago, Ill., a corporation of Illinois

Application August 17, 1936, Serial No. 96,480

20 Claims. (Cl. 105—315)

The invention relates to railway sleeping cars and has particular reference to the interior arrangement involving the use of metal partitions designed to convert the customary open berth sections upon opposite sides of a central aisle into private upper and lower compartments with separate entrances and dressing spaces for each compartment with provision for a foldable stairway under control of the occupant for convenient access to the upper compartment.

An important feature of the invention resides in the system of aisle partitions arranged longitudinally of the car and adapted for use with berth sections of the standard Pullman car whereby the seats of the section, when made up as a berth, will supplement the partition to complete the lower compartment, and the pivoted bunk above them, when lowered, will form with said partition the upper compartment of the section, each berth section being separated from next adjacent section by transverse partitions connecting the longitudinal partitions to adjacent car sides. Another feature of the invention utilizes the air conditioning equipment of the car for ventilating the compartment spaces, the circulation of the air in the compartments being facilitated by the use of louvered panels in the aisle partitions providing communication with the air outside the compartments.

The installation permits the application of lavatory equipment for each compartment and toilet accessories for the convenience of the occupants, certain of the equipment being available for use during periods when upper compartment is not made up for occupancy, as will hereinafter appear.

The foregoing and other objects of the invention are achieved by the mechanism illustrated in the accompanying drawings, in which—

Fig. 1 is a general plan of a sleeping car equipped in accordance with the invention, showing a series of the section compartments arranged upon opposite sides of a central aisle, a bedroom and a fixed compartment opening to a side aisle, additional toilet facilities supplementing those of the section compartments, and space for air conditioning apparatus upon opposite sides of a second central aisle;

Fig. 2 is a general perspective view from the aisle of the car showing the compartment aisle partition in position with the sliding door opened and the hinged panel portion swung back to expose the section interior and seat at one end of the section;

Fig. 3 is a similar view from the inside of the

section showing the seat at the end opposite that indicated in Fig. 2 and adjacent fixed portion of the aisle partition fitted with foldable washstands for upper and lower compartments and the hinged panel portion closed and sliding door open to show the seat of Fig. 2 in a like section upon opposite side of the aisle normally covered by the hinged panel;

Fig. 4 is a view similar to Fig. 2 showing the section converted into upper and lower compartments and the aisle partition adjusted to provide separate entrances to the compartments with dressing space curtains operatively secured to the partition and showing, also, the foldable stairway to upper compartment removably mounted upon the partition at one side of the entrance to lower compartment;

Fig. 5 is an elevational view of the aisle partition from the inside of a berth section with a vertical section thru the transverse partitions taken on line 5—5 of Fig. 1, and showing the sliding door closed and its position in the assembly with respect to the opening to the upper compartment and location of the lavatories;

Fig. 6 is a similar view of the aisle partition from the aisle side showing the entrance to the upper compartment closed by a louvered flexible sliding door, the view showing the door in the partition of the next adjacent section in partially raised position, the relative positions and proportions of upper and lower compartment windows being indicated in broken lines;

Fig. 7 is a vertical transverse section of one side of the car taken on line 7—7 of Fig. 6, thru the aisle partition sliding door showing the mounting of the door and dressing space curtain upon the partition, the foldable lavatories closed upon the inner face of the partition with respect to lowered and raised positions of the upper bunk and bunk apron, and the observation windows and adjustable shutter arrangement in the car wall of the upper compartment and showing the relation of such windows to those of the lower compartment;

Fig. 8 is a similar view showing the lavatories on the partition opened for use, the upper bunk having been previously lowered, and the upper lavatory dropped from its normal closed position shown in Fig. 7, and the relative positions of the observation windows of the upper compartment and the curtain balancing roller casing;

Fig. 9 is a similar view taken on line 9—9 of Fig. 6, thru the hinged panel portion of the partition and the flexible sliding door within its housing beneath the car roof, and showing in broken

lines the ladder and curtain operating mechanism providing dressing space for upper compartment;

Fig. 10 is a vertical transverse section thru the upper portion of the sliding door for the lower compartment taken on line 10—10 of Fig. 5, and showing the louvered closure panel for the upper compartment mounted independently of the sliding door and forming a portion of the compartment partition at the aisle when the sliding door 10 is open;

Fig. 11 is a horizontal section thru the bottom support and guide for the closure panel taken on line 11—11 of Fig. 10, showing the combination panel support and light excluding bar wedged 15 in position between the free edge of the upper bunk and the aisle partition post members;

Fig. 12 is a fragmentary elevational view of one of the fixed guide rails and supports for the flexible sliding door and covered by an underlying 20 plate to provide a housing for the door and taken on line 12—12 of Fig. 5, showing its junction with a continuation of the guide rail on the standard rising from the free edge of adjacent hinged panel portion of the aisle partition;

Fig. 13 is a horizontal section thru the guide rail standard on the hinged panel portion of the aisle partition taken on line 13—13 of Fig. 5, showing the partition post and guide rail assembly;

Fig. 14 is a vertical transverse stepped section thru the lower and intermediate portions of the hinged panel taken on line 14—14 of Fig. 6, on an enlarged scale, better to show the interlocking rail recessed to receive a locking tongue on 35 the foldable stairway removably supported upon the bottom rail of the panel;

Fig. 15 is a horizontal section thru the sliding door and framing posts of the aisle partition taken on line 15—15 of Fig. 6, showing the method 40 of removably securing the side marginal edges of the dressing bay curtain indicated in Fig. 4, for the lower compartment with the locking grooves in the posts;

Fig. 16 is an enlarged fragmentary vertical 45 sectional view taken transversely thru the upper rail of the sliding door and partition lintel on line 16—16 of Fig. 6, showing the roller door hanger and the trackway for supporting the rollers;

Figs. 17 and 18 show the hanger rods for the dressing bay curtain indicated in Figs. 4 and 15, and depicting, respectively, the extended operative position of the curtain rod with sliding door 50 open and the collapsed position of the rod when sliding door has been closed; and

Fig. 19 is a horizontal sectional view on line 19—19 of Fig. 5, thru the partition post supporting the washstands in upper and lower compartments as illustrated in Figs. 7 and 8, the hot and cold water supply pipes, the drain, the sliding door bottom rail, the rear bumper arrangement, and the removable outer panel giving access to said parts.

In said drawings, 10 represents a sleeping car having berth sections 11 arranged upon opposite sides of a central longitudinal aisle 12 defined by a pair of partitions 14 extending from a bulkhead 15 at the vestibule 16 adjacent one end of the car to the bulkhead 17 separating the berth section area from the compartment and bedroom spaces 18 and 19 rearwardly thereof. Forwardly of bulkhead 15 the vestibule 16 provides an entrance to the car thru door 21 and retractile 70 steps 22, access to the central aisle 12 being had

thru door 23 of the bulkhead. From the vestibule a central passageway 24 leads to the women's toilets 25 and 26 on opposite sides of the car and to entrance 27 at the front end of the car giving access to other cars of the train. From the vestibule 16 access is had to linen lockers 30 and 31 and switchboard lockers 32.

Entrance to space rearwardly of bulkhead 17 is had thru door 35 leading to side aisle or passageway 36 at the side of the car giving access to 10 compartment 18 and bedroom 19 thru doors 37 and 38, respectively, and to a second vestibule 40 thru doorway 41 giving access to another entrance 42 and steps 43 on the opposite side of the car. From vestibule 40 access is had to men's 15 toilets 44, 45 and 46 and through a second central passageway 47 to compartments 49 and 50 housing the air conditioning apparatus and to rear door 51. The vestibule 40 accommodates a porter's seat 52 and gives access to lockers 53 20 containing electric control equipment for the air conditioning system.

Although eight berth compartment sections are indicated in the present embodiment, any number of such sections may be provided, and the 25 position of the sections with respect to other facilities of the car may be adapted to any operating condition.

The berth sections 11 are fitted with the customary pair of confronting seats 60 arranged for adjustment by the occupant to a lounging position and convertible to provide a lower berth by shifting the seat cushions 61 towards each other with their respective supporting bars 62 slidably mounted upon brackets 63 and 64 secured respectively to the car side and seat ends 65, as best shown in Figs. 2, 4 and 7 thru 9. The seat back cushions 66, pivotally connected to the seats, likewise assume horizontal positions in the space between the shifted seat cushions 61 and section 40 partition 13 in a manner usual to such arrangements to form with the seat cushions a support for the bedding 67 as in Fig. 4. As indicated best in Fig. 3, the seat back cushions 66 may be fitted with additional arm rests 68 pivotally nested in 45 pockets 69 in the seat backs from which they may be withdrawn to supplement the arm rests 70 at the side wall position. The pivoted head rest cushions 71 are raised from their normal position to provide the customary shelf for belongings of the occupant, as in usual practice, and supplement the collapsible fabric shelf (not shown) spanning the section above the lower berth and removably hung from socket plates 72 in partitions 13. 55

The upper bunks 80 are pivotally secured to the partitions 13 above the seats 60 at the car sides as in general practice and adapted, when lowered, to provide upper berths as best shown in Figs. 4 and 7 thru 9. In their lowered position, the bunks 80 are chain-supported at their free edges from the usual berth sheaves 82 mounted on brackets 83 fixed to the roof framing as indicated in Fig. 3. When the upper bunks 80 are 60 in raised position, as shown in Figs. 2, 7 and 9, the space between the free edge thereof and the ceiling 78 is closed by an apron 84 pivoted at 85, and, when the bunks are lowered, the aprons 84 are raised and held by latches 86 in the partitions 13 as shown in Figs. 7 thru 9, until released by the attendant upon raising of the bunks. It will be noted that that portion 87 of the apron panel 84 projecting rearwardly beyond the pivot 85 is cut away at the housing 78 for 70 75

the flexible sliding door 88, as shown in Fig. 9, to insure complete closure of the space between one edge of the housing and opposite partition for the depth of the housing above the pivotal axis of the apron.

As shown in Figs. 1, 3, and 7 thru 9, the aisle partitions 14 are spaced from the seat ends 65 and the free edges of upper bunks 80 to provide upper and lower compartments of greater width than possible with constructions wherein the seat ends constitute portions also of the partitions and, incidentally, to provide, with respect to the bunks, sufficient clearance for movement thereof through the arc indicated at 89 in Figs. 7 and 9, and to accommodate the combination screen support and light-excluding bar 90 shown in Figs. 10 and 11, to be later described. For the purpose of the present construction, the partitions 14 are rigidly secured to roof framing longitudinals 91 at the ceiling position and to the floor 20, and stiffened at spaced intervals by posts 92 and 93 defining the central door opening 77 to the lower compartment, and post 94 forming with post 93 the sides of the opening 76 to the upper compartment, post 94 being adapted for connection to adjacent transverse section partitions 13 and through them to the side walls 75, to the end that the walls enclosing the berth spaces 11 shall be sufficiently rigid to withstand the loads imposed in service operations.

The areas of the aisle partitions 14 incident to the several berth sections comprise each a fixed panel portion 95 having a permanent inner wall member 96 secured to posts 92 and 94 and an outer wall member 97 detachably secured to said posts with sections 98 and 99 of the posts, respectively, removable with the panel member as best shown in Figs. 15 and 19, by the removal of screws 73 and 74, respectively. In the present embodiment, the fixed section of post 92 is fitted with a drain 59 from upper and lower compartment lavatories 57 and 58, respectively, when such facilities are incorporated, as best shown in Figs. 3, 5, 7 thru 9, 15 and 19, and the outer wall panels 97 are detachable for the purpose of facilitating inspection and maintenance of such equipment.

The space thus provided between inner and outer panels 96 and 97 is arranged to accommodate the sliding door panel 100 for closing the opening 77 together with upper track 101 for supporting the door and a bottom rail 102 for guiding the lower edge of the door, as shown in Figs. 5, 7, 8, 15, 16 and 19. The door track 101 forms, also, the rigidifying means for the door opening lintel 103 since it extends from post 94 at partition 13 to adjacent side of fixed extension 104 of post 93.

The partition is further made up of a hinged panel portion 105 pivotally supported to swing into the aisle in a horizontal plane on hinges 106 secured to the fixed panel post 94 at the partition 13 to facilitate access to the section by the attendant for making up the compartments for night use or restoring the section for day travel, so that the panel will move from the closed position indicated in Fig. 4 to the open position overlapping the fixed panel 95 of adjacent section, as shown in Fig. 2. The panel is held closed by locking bars 107 mounted for reciprocation vertically in movable post 93 and adapted for engagement with upper keeper 108 at the lower end of fixed post extension 104 and the lower keeper 109 secured to the floor. For holding the panel open, a spring finger latch 110 is se-

cured to the fixed panel portion 95 of adjacent section within a recess 111 and flush with panel surface, all as best shown in Figs. 2, 4, 6, 14 and 15. The finger 112 of the latch is provided, at its free end, with a knob piece 113 adapted, when the finger is extended as shown in dotted line position, to engage the groove 114 in the post 93 to hold panel open until released by the attendant to close. The hinged panel 105 extends upwardly from the floor to approximately the upper bunk 10 position to provide a threshold 115 for opening 76 giving access to the upper compartment when upper bunk has been lowered as shown in Figs. 4 and 9.

The post 93, movable with panel 105, projects upwardly therefrom in the form of a standard beyond threshold 115 for engagement with fixed post extension 104 to provide the framing for one side of the opening 77 to the lower compartment. To establish continuity with post 93 extension 104, the projected portion of post 93 is formed with an abutment 116 designed to insure alignment of the guideway 117 on the door post 93 with the relatively fixed guideway 118 on post extension 104, as indicated in Figs. 3, 5 and 12, so as to provide a continuous runway for the flexible sliding door 88 across the joint between such guideways at one side of opening 76 to the upper compartment. The companion guideway 119 on the opposite side of opening 76 is fixed throughout its length and extends, from the curtain balancing roller casing 56 of the door housing 78 at the side of the car adjacent the ceiling 79, to the threshold 115 on the hinged panel 105 of the aisle partition as best shown in Fig. 9. The guideway 118, a portion of which is indicated in Figs. 5, 12, 13 and 17, also extends to the curtain balancing roller casing 56 of the housing and, with its companion guideway 119, provides the support for the flexible sliding door 88 closing the opening 76 to the upper compartment.

Both guideways are of channel shape in cross-section with the flanges 55 extended beyond the web of the channel to provide attaching flanges 54 securing the housing underplate 120 extending below the ceiling 79 and connecting the guides from the curtain balancing roller casing 56 to a point adjacent the curved portion 48 in the guides at the partition. To enable the bottom rail 39 of the flexible sliding door 88 to negotiate the curve 48 in the guides, the underplate 120 of the housing may be flared downward from the plane of the plate, if necessary, or a separate underplate panel 121 substituted as shown in Fig. 12 to provide the required clearance for the rail. The guide rails 117 and 119 are each of them bent laterally at the threshold 115, as shown in Fig. 5, to provide fixed and movable portions 122 and 123, respectively, complementing each other to form the threshold, the flanges 55 being secured to the door panel by welding or otherwise, the portion 122 being secured to fixed post 94 and the part 123 to the door panel 105. At the threshold position the outer flanges 55 of the guide extensions 122 and 123 are cut away as shown in Figs. 3 and 13 and the outer sheet of the panel 105 extended upwardly at 124 to form with the inner flanges 55 of the guides the groove 125 of the threshold 115 to receive the bottom rail 39 of the flexible sliding door 88 and to provide a suitable finish moulding for the upper margin of the panel, the broad face presented by the inner flanges 54 and 55 providing a convenient engaging surface for the opposing face 126 of the light-excluding bar 90 wedged between said

flanges and the fender 81 at the free edge of the bunk 80.

The remainder of the aisle partition 14 provides for the closure of the opening between the fender 81 at the free edge of the bunk 80 when lowered and the lintel 103 at the sliding door opening 77 when sliding door 100 is open for access to lower compartment. For this purpose, there is provided a fixed louvered screen 130 5 removably mounted in an upper guide member 131 on the rear face of lintel 103 and supported from lower guide member 132 on the light-excluding bar 90 supported between the upper bunk 80, when lowered, and the partition, as best shown in Figs. 10, 11 and 16. The screen 130 is formed 10 with a frame having the usual stiles 127, upper rail 128 and the lower rail 129 with the louvered area between. The screen is slid into position 15 between the guide members 131 and 132 from one end thereof and, for convenience of assembly, preferably from the end adjacent the opening 76 to the compartment.

The combination light excluder and screen supporting bar 90 extends preferably from one transverse partition 13 to the next adjacent one 20 to prevent longitudinal displacement of the screen-supporting guide 132 with respect to the permanent upper guide member 131 when the screen is being adjusted to position. In its present form, the bar 90 is angular in cross-section 25 and preferably of wood, although it may be of extruded metal or rolled shape, and covered with carpet or other cushioning fabric 133. In its operative position as a light excluder, the bar is arranged with a leg member 134 fitted into the 30 space between the fender 81 at the free edge of the bunk 80 and the aisle partition to exclude from a compartment any light or sound emanating from the other compartment of the section. The member 134 is removably held in operative 35 position by a companion member 135 extending laterally of the first member to seat upon the bunk fender 81 for support, as best shown in Fig. 10. The bar 90 is of constant cross-section except at the fixed post 92 where it is notched-out at 136 to accommodate the lavatory drain 40 and washstand equipment 57 and 59 mounted on post 92 for use in upper compartment, when such installation is made, as indicated in Fig. 11.

When lavatory equipment is installed for use 45 in the compartments, as indicated in Figs. 5, 7, 8 and 19, the post 92 and fixed inner panel 96 may be utilized for the support of the upper and lower lavatories 57 and 58, the upper lavatory 57 being mounted to clear the bunks 80 when bunks are 50 lowered from their raised position as illustrated in Fig. 7. In this figure, the washstand 57 in the upper compartment is mounted on brackets 137 vertically slidable in guides 138 on the post 92. In its raised closed position, the lavatory unit 55 does not interfere with the raising and lowering of bunk 80 and apron 84 since their respective paths of movement 89 and 94 are well inside the lavatory space in its raised position. The lavatory is lowered to normal position for use only 60 after the bunk has been lowered as indicated in Fig. 8, in which position the lavatory basin 33 may be opened by the occupant of the compartment until the unit is raised by the attendant 65 to permit raising of the bunk when released from retaining latch 6 on partitions 13.

The lower lavatory 58 is fixed against vertical movement from its normal position and is available for use at all times. Both upper and lower 70 lavatories are supplied with hot and cold water 75

circulated in hot and cold water pipes 28 and 29 respectively, that portion of the pipes leading to the upper lavatory 57 being flexible to accommodate the vertical adjustments of that unit, the pipes being connected to a suitable source of 5 water supply, not shown, both lavatories being serviced by the common drain 59 discharging through the floor of the car as indicated in Fig. 5. The lower compartment lavatory unit 58 is fitted with a mirror 139 positioned with the unit in 10 the plane of the post 92 and above the washbasin, but in the case of the movable upper compartment lavatory unit 57 the mirror 140 is hingedly supported upon the unit laterally thereof and in the 15 plane of the inner panel 96 of the aisle partition 15 to permit the lavatory to be raised to clear the bunk 80 and apron 84 as aforesaid, and, in both units, the mirrors are mounted for any desired adjustment in a horizontal plane.

The door track 101 forms part of a unitary 20 assembly preferably of extruded metal secured to the aisle partition, as best shown in Fig. 16. The track projects outwardly from a base plate 141 secured to the inner face of the outer sheet 25 of the partition and is formed to receive the rollers 142 journaled in hangers 143 secured to the door 100. Above the rollers is a hood place 144 projecting from the base plate 141 and terminating at its outer edge in a depending flange 145 providing a spacing plate and securing means for 30 the inner sheet of the partition and serving to rigidify the lintel 103 from fixed post 94 to post extension 104 and further reenforcing upper guide member 131 for the screen 130. The inner and outer sheets of the partition forming the lintel 35 103 at the door opening 77 are also stiffened at their margins by flanges 146, separately formed or integral, as indicated in Fig. 16.

The partitions 14 are made up of panels with 40 louvers 147 shaped and disposed to prevent a view of the compartment interior from the aisle but allowing the circulation of an adequate volume of air therethrough, as best shown in Figs. 2 thru 4, 10, 14, 17 and 18. As indicated in Figs. 2, 3, 10 and 14, the louvers are preferably of modified Z-section mounted with their inner and outer flange 45 portions 148 and 149, respectively, lying in parallel vertical planes and connected by a web portion 150 disposed at an obtuse angle with respect to such flanges, said flanges being formed with wing portions 151 inwardly directed and spaced from contiguous wings and flanges of adjacent louvers to define air passages 152 substantially offset to obstruct the view. Intermediate 50 the upper and lower rails of the hinged panel 105 is inserted a rail member 155 designed to simulate the louver slats 147 above and below it with its upper and lower margins formed with louver flanges 148 and 149 and wings 151, respectively, and provided with a groove 153 defined on its 55 upper side by a downwardly and outwardly protruding lip portion 154 adapted for interlocking engagement with a removable stairway hereinafter to be described.

The flexible sliding doors 88 for the openings 60 65 to upper compartments are made up of louvers 156 connected in spaced relation with their ends movable in guides 117, 118 and 119. The louvers in the sliding panels are preferably of general V-shape disposed with their apices extending into 70 the space beneath the louvers above them when doors are closed with their bottom rails 39 in grooves 125 of the threshold 116 shown in Figs. 3, 5, 6 and 9. The panels thus formed are connected to spring curtain rollers 157 in casings 66 75

5 by means of straps 158 adapted for winding upon the rollers to balance the weight of the panels to facilitate operation of the doors. Suitable fastening means 159 under control of the occupant may be secured to the door rail 39 for locking the doors closed. As best shown in Fig. 9, the curtain balancing roller casing 56 is positioned well above the observation window 225 of the upper compartment 7 and provides ample 10 clearance for the operation of the shutters 227 slidably mounted in the window frame 228.

10 The sliding door 100 for the lower compartment moves between post 93 on the hinged panel 105 and fixed post 94 of the partition when hung as before outlined. To insure quiet operation 15 of the door, preferably the front and rear edges of the door are fitted with cushioning pieces 160 and 161 for engagement, respectively, with posts 93 and 94, the latter having secured to it the rubber bumper 162, all as shown in Figs. 11, 15 and 19, cushion 160 nesting in groove 114 on post 93. This door also is fitted with suitable latching mechanism 163 under control of the occupant for locking the door closed. The door at the bottom 20 is held from lateral shifting with respect to partition wall members 96 and 97 by downwardly opening channel guides 164 on the door adapted to receive upstanding flange 165 on the bottom rail 102 on the partition as shown in 25 Figs. 2, 7, 8 and 19.

30 These doors serve also to actuate curtain rods for supporting dressing bay curtains presently to be described. For this purpose, the doors are fitted at their free edges adjacent the top rail 35 of the doors with brackets 169 secured to the door and projecting therefrom outwardly and terminating in upwardly directed fingers 170 and 171 spaced apart outwardly of the face of the door and rigid as shown or of roller type, to receive 40 between them a bar 172 twisted with its respective ends substantially at right angles to each other and having pivot bearings 173 journaled in socket brackets 174 and 175 secured to posts 92 and 104 of the partition 14 as shown best in Figs. 2, 4, 17 and 18. Rigidly secured to and connecting 45 the respective pivot bearings 173 is a ball-shaped rod 176 forming with said bar a frame adapted for movement in an orbit about an axis through said pivot bearings so that upon shifting 50 of the door 100 the fingers 170 and 171 on door brackets 169 will bear upon opposite faces of the twisted bar 172 and hold the section of the bar thus engaged upright between them. In the 55 open door position indicated in Fig. 17, the curtain rod 176 will be disposed substantially horizontally in the plane of the bar 172, but, upon closing movement of the door, the bracket fingers 170 and 171 will traverse the length of the bar to bear, progressively, upon respective sides 60 thereof and cause the bar to rotate axially on its bearings 173 and carrying with it the curtain ball 176 until the rod assumes a position substantially vertically in the plane of the bar 172 as shown in Fig. 18 with the door closed.

65 Upon the ball rods 176 are hung the curtains 177 to provide a private dressing bay for the occupant of the lower compartment 8, as best shown in Figs. 4, 7, 8 and 15. These curtains are preferably slit for the greater portion of 70 their length, the divided portions being secured together by any suitable fastening means 178 such as buttons, as shown, or clips. Provision is made to safeguard the feet of the occupant from injury while dressing or disrobing behind 75 the curtain by the accidental treading upon them

5 by persons passing through the aisle. The curtain is weighted by means of wedge blocks 2, preferably of rubber, secured to the curtain with their base portions 3 at the floor of the car, the inclined portions 4 being presented outwardly and vertical rear portions 5 directed inwardly. The blocks are held vertically upon their bases by the curtain which prevents overturning of the blocks upon the feet of the occupant under thrust of loads applied to the inclined front faces 4 so 10 that the blocks will be caused to slide upon their bases. Further privacy to the occupant of the compartment is assured by means provided for removably securing the curtains to the partition at the sides of the compartment opening where- 15 by the curtains form virtually flexible extensions of the compartment spaces for use when doors are open. As best shown in Figs. 2, 4, 6, 15 and 17 thru 19, posts 92 and 93 are formed with retaining grooves 180 designed to receive con- 20 tiguous edges of the curtains 177 and with portions of the grooves open at intervals along their length, preferably at the upper end of the posts as at 181 and intermediate points 182 and 183 to admit curtain edge bound core retaining 25 strips 184.

25 The curtain edge strips 184 are in lengths corresponding to the distance between the openings in the post grooves and are spaced apart lengthwise a distance equal substantially to the length 30 of the respective openings 181, 182 and 183, so that the operation of attaching the curtains to the partition may be initiated by inserting first the lower end of the top strip in opening 181 at the upper end of adjacent post and drawing same 35 downwardly within the groove 180 until the upper end of second opening 182 is reached, whereupon the lower end of the second strip may be inserted in opening 182 and the strip threaded 40 into that portion of the groove between openings 182 and 183, and the operation repeated with respect to the third length of strip the lower end of which is inserted in lower groove opening 183 and drawn downwardly into the groove portion 45 between the lower end of opening 183 and lower end of the post, the whole curtain being supported by the curtain frame pivotally held in the bearings 174 and 175, the frame consisting of the twisted bar 172 and ball-shaped rod 176.

50 The operation of removing the curtain is executed in reverse sequence, the lower section of edge strip is first withdrawn from the section of groove below opening 183 followed by withdrawal of the intermediate strip from the groove below opening 182, the withdrawal of the upper edge strip from the groove below the upper opening 181 being effected by the removal of the curtain-supporting frame from its bearings 174 and 175. The removal of the curtain frame from its 55 bearings is accomplished by the release of retaining clip 186 by disengaging it from spring latch 187 and rotating the clip about its pivot 188 in the plane of the clip to uncover the bearing 173 in socket of bracket 175; after the bearing is 60 lifted from its socket, the frame is shifted axially to withdraw the other bearing 173 from the other socket bracket 174, whereupon the frame with curtain 177 attached may be stored with the bedding of the section within the upper berth bunk 80 during day travel and reassembled when 65 section is made up for night occupancy.

Similarly, the curtain 190 for the upper compartment opening 76 is hung from a ball-shaped rod 191 having terminal bearings 192 pivotally mounted in socket brackets 193 and 194 secured, 75

respectively, to posts 184 and 94 of the partition 14 in a plane above the bearing brackets 174 and 175, as best shown in Figs. 2, 4 and 9. The curtain 198 is preferably hung in one piece and mounted for sliding upon the rod from one side of the compartment opening 76 when access to or egress from compartment 7 is desired. The curtain is held fixed along one of its edges to the partition post 94 formed with a groove 195 which, in view of the relatively short curtain 198, may be of lesser length than the grooves securing the relatively long curtain 177. The curtain is provided with an edge strip corresponding to that shown on the curtain 177 but preferably in one piece the full length of the curtain and assembled with post 94 by inserting the bottom end of the strip in opening 196 at the upper end of groove 195 and drawing downwardly within the groove for a distance approximating the length of the curtain. To prevent the curtain from fouling at the curtain bail 191, the groove 195 is fitted with a support 197 for the lower end of the edge strip so that the strip will support the curtain at the bail when bail has been dropped to the collapsed position shown in Fig. 9 from that indicated in Fig. 4.

It will be noted that the bail 191 is provided at one end with a arm portion 198 projecting inwardly from the pivotal axis of the bail and formed with an eye piece 199 to receive one end of a cable, rod or chain 200 connected at its opposite end with a removable stairway 189 foldable against and supported upon the swinging partition panel 105 as best shown in Figs. 4, 9 and 14. The connection 200 is attached to the stairway by means of a clip 202 secured preferably to the underside of the upper tread 201 a distance at least as great outwardly from the tread hinge 203 as the length of arm 198 on the curtain bail 191 so that the folding of the ladder against the partition will release the tension on connection 200 and move clip 202 upwardly a distance sufficient to allow curtain bail arm 198 to move upwardly under the weight of the curtain. Conversely, the unfolding of the stairway will exert a pull on curtain bail arm 198 thru connection 200 to move the arm downwardly to raise said curtain rod and the curtain 198 as indicated in Figs. 4 and 9. The operation of raising the curtain 198 is effected by unfolding of stairway 189 when access to or descent from the upper compartment 7 is desired, or when dressing or disrobing, during which period the upper tread 201 serves as a convenient standing platform for the occupant shielded by the curtain when drawn for use, the movements of the occupant being facilitated by the use of the handhold 230 adjacent the door opening.

The stairway is removably mounted upon the hinged panel portion 105 of the partition to one side of opening 77 to the lower compartment 8 and directly beneath opening 76 to the upper compartment, as best shown in Figs. 4, 9 and 14. The stairway is assembled with its inner stile portion 205 resting with its lower end upon ledge 206 of the panel and held by the retractile plunger 207 of latch 208 in the panel and its upper end interlocked with rail member 155 on the panel. For this purpose, the upper end of the stile 205 is fitted with a protruding tongue plate 209 projecting inwardly and upwardly within groove 153 in the rail member 155 and extending along the stile member for a substantial distance and terminating with the groove in the wall of the panel, the upper end of the stile 205 being extended be-

yond the tongue plate 209 for abutment with adjacent stile of panel 105 and to provide support for the upper tread 201 widened for use as a platform, as shown in Figs. 4 and 14.

The outer end of the platform tread 201 is supported by the outer stile 204 having an upper end coextensive with the platform, the outer stile being of greater length than the inner one and extending from the platform to the floor 20 of the car and below the level of ledge 206 of the panel, the stile being further connected to the lower and intermediate portions of the inner stile 205 by additional treads 210 and 211, respectively. The treads are pivotally secured at their inner upper sides to adjacent stile by hinges 212 and at their outer lower sides to the outer stile by hinges 213, the relatively wide platform tread 201 being secured at its outer lower side by a hinge 214, so that upon upward movement of the outer stile it will be directed inwardly toward the partition to rest with its lower end within the space above the ledge 206 thus to lie substantially flush with the panel 105 when stairway is folded.

As best shown in Fig. 9, the stairway is held normally folded by means of a lifting arm 215, spring actuated, to exert a force on the underside of the platform tread 201 through a roller 216 designed to have pressure contact with the tread in all of its movements. The stairway is also fitted with a hand rail 217 secured to the outer stile and projecting upwardly to provide a handhold above the platform 201 and extending along a portion of the stile below the platform, as best shown in Figs. 4 and 9. It will be noted that the stairway, as a whole, is held to the partition by the interlocking engagement of the tongue plate 209 and the underside of the downwardly and outwardly protruding lip portion 154, by the abutment of the stile against adjacent stile of the panel 105, and by the plunger 207 on ledge 206 of the panel, the hand rail 217 and platform 201 being positioned inside of the curtain 198 in folded and open positions of the stairway 189 and of the curtain. The stairway is removable when collapsed and stored with the bedding and curtains of the section within the upper berth bunk 80 during day travel and placed in position when section is made up for night occupancy.

As first above stated, the air conditioning equipment of the car is utilized for ventilating the compartments. This is accomplished by introducing conditioned air from a main duct 220 at the ceiling of the car outside of the compartments downwardly through branch ducts 221 in partitions 13 communicating with registers 222 and 224 opening into the upper and lower compartments, respectively, and under control of the occupants. The air from the main duct is conveyed, under pressure, through lateral connecting ducts 223 at the several sections, all as best shown in Figs. 5, 7, 8, 9 and 19, and expelled from compartments through the louvered partitions to the aisle, the air thus expelled being recirculated with fresh air conditioned by suitable apparatus, not shown, in compartments 49 and 50 upon opposite sides of the passageway 47 at one end of the car shown in Fig. 1.

For the further convenience of the occupants of the upper compartments 7 of the sections, observation windows 225 are provided in the car side 75 immediately above the level of the bunks 80 and substantially above the level of the tops of windows 9 of the lower compartments 8, as

best indicated in Figs. 6, 7 and 9. The windows 225 are spaced apart by wall panel portions 226 and fitted with movable shutters 227 slidably mounted in pairs in the frames 228 which are coextensive with both windows 225 and intermediate panels 226 so that one or the other of the windows may be fully uncovered or both of them only partially uncovered at one time, since the several shutter panels 227 are substantially as long as but one of said windows, the operation of the shutters and their disposition being under the control of the occupant. The window frames 228 are positioned substantially midway between section partitions 13 and below the curtain bal-
15 ancing roller casing 56 controlling the flexible sliding door 88 to the upper compartment, and will permit the use of collapsible clothes racks of the type shown in Pearson Patent No. 1,621,558 of March 22, 1927, when hung between fixtures 20 229 on opposite partitions 13.

It will be noted from the foregoing that although the interior arrangement disclosed has been adapted primarily for use in cars streamlined as to contour with their side walls 15 sloping upwardly and inwardly as shown in Figs. 7 and 9, it is obvious that certain features of the installation may be utilized in cars having vertical side walls without change.

What is claimed is:

30 1. In a car having berth sections upon opposite sides of a central longitudinal aisle, partitions spaced apart laterally of the car and disposed longitudinally thereof to define said aisle, partitions disposed transversely of the car separating said berth sections and connecting the aisle partitions to the respective car sides, and means carried by said aisle partitions for converting said berth sections into compartments comprising hinged and sliding portions respectively, said 40 sliding portion providing an entrance to one compartment, a vertically slidable portion providing entrance to another compartment, and means on said hinged portion affording access to said last named entrance.

45 2. In a car having partitions disposed longitudinally of the car and spaced apart laterally to define a central aisle, berth sections upon opposite sides of said aisle, panels forming said partitions for converting said berth sections into compartments having hinged and sliding portions respectively, said sliding portion providing an entrance to one compartment, a vertically slid-
50 able portion providing entrance to another compartment, and means on said hinged portion affording access to said last named entrance.

55 3. In a car having partitions disposed longitudinally of the car and spaced apart laterally to define a central aisle, berth sections upon opposite sides of said aisle, partitions disposed transversely of the car for separating said sections, pairs of confronting seats in the respective sections convertible to form lower berths, bunk members pivotally mounted between said transverse partitions to provide upper berths, panels having hinged and sliding portions respectively forming said aisle partitions for converting said upper and lower berth spaces into compartments, said sliding portions affording entrances to said lower berths, vertically slidable portions providing entrances to said upper berths, and means on said hinged portions affording access to said upper berth entrances.

70 4. In a car having partitions disposed longitudinally of the car and spaced apart laterally

to define a central aisle, upper and lower berth sections upon opposite sides of said aisle, panels forming said aisle partitions for converting said berth sections into upper and lower compartments with separate entrances to each, and collapsible stairways removably mounted on said partitions for giving access to said upper compartments. 5

5. In a car having partitions disposed longitudinally of the car and spaced apart laterally to define a central aisle, upper and lower berth sections upon opposite sides of said aisle, louvered panels forming said aisle partitions for converting said berth sections into upper and lower compartments, separate entrances to each at the 15 end and intermediate the ends, respectively, of said upper and lower compartments.

6. In a car having partitions disposed longitudinally of the car and spaced apart laterally to define a central aisle, upper and lower berth sections upon opposite sides of said aisle, fixed and movable panels forming said partitions for converting said berth sections into upper and lower compartments having independent end and intermediate entrances, respectively, certain of 25 said movable panels being slidable to close said entrances.

7. In a car having partitions disposed longitudinally of the car and spaced apart laterally to define a central aisle, upper and lower berth sections upon opposite sides of said aisle, fixed and movable panels forming said partitions for converting said berth sections into compartments having independent end and intermediate entrances, respectively, certain of 30 said movable panels being slidable vertically to close the entrance at the end of the upper compartments and one slidable horizontally to close the intermediate entrance to the lower compartments, respectively. 40

8. In a car having partitions disposed longitudinally of the car and spaced apart laterally to define a central aisle, berth sections upon opposite sides of said aisle, partitions disposed transversely of the car for separating said sections, pairs of confronting seats in the respective sections convertible to form lower berths, bunk members pivotally mounted between said transverse partitions and adapted to be lowered to provide upper berths, light-excluding members 45 between said aisle partitions and the free edges of said bunks, and panels forming said aisle partitions for converting said upper and lower berth spaces into compartments. 50

9. In a car having partitions disposed longitudinally of the car and spaced apart laterally to define a central aisle, upper and lower berth sections upon opposite sides of said aisle, fixed and movable panels forming said aisle partitions for converting said berth sections into upper and lower compartments with separate entrances to each, collapsible stairways removably mounted on said partitions for giving access to said upper compartments, collapsible dressing bay curtains 60 removably mounted in said partitions, means 65 operable upon folding or unfolding of the stairways for actuating the curtains for the upper compartments, and means operable by the movements of one of said panels for actuating the curtains for the lower compartments. 70

10. In a car having partitions disposed longitudinally of the car and spaced apart laterally to define a central aisle, upper and lower berth sections upon opposite sides of said aisle, panels and post members forming said partitions for 75

- converting said berth sections into upper and lower compartments with separate entrances to each, and foldable lavatories in said compartments operatively secured to respectively adjacent post members of the partitions.
5. 11. In a car having partitions disposed longitudinally of the car and spaced apart laterally to define a central aisle, berth sections upon opposite sides of said aisle, individual doorways to 10 said berth sections from the aisle, curtains at the doorways, means supporting said curtains, and means securing said curtains comprising edge-retaining strips on the curtains entered in curtain-retaining grooves in said partitions at 15 opposite sides of the respective doorways.
12. In a car having partitions disposed longitudinally of the car and spaced apart laterally to define a central aisle, section rooms upon opposite sides of said aisle, individual doorways in 20 the partitions to said rooms, sliding doors for said doorways, curtains at the doorways, means supporting said curtains, and means securing said curtains comprising edge-retaining strips entered in curtain-retaining grooves in said partitions at opposite sides of the respective doorways.
25. 13. In a car having partitions disposed longitudinally of the car and spaced apart laterally to define a central aisle, individual compartments upon opposite sides of said aisle, doorways in the partitions to the respective compartments, sliding doors at the doorways, curtains at the doorways, means supporting said curtains, and means securing said curtains comprising edge-retaining strips entered in curtain-retaining grooves in said partitions at opposite sides of the respective doorways.
40. 14. In a car having partitions disposed longitudinally of the car and spaced apart laterally to define a central aisle, individual compartments upon opposite sides of said aisle, stiles defining doorways in the partitions to the respective compartments, curtains at the doorways, means supporting said curtains, and means securing said curtains comprising edge-retaining strips entered in curtain-retaining grooves in said stiles at opposite sides of the respective doorways.
45. 15. In a car having partitions disposed longitudinally of the car and spaced apart laterally to define a central aisle, individual compartments upon opposite sides of the aisle, doorways in the partitions to the respective compartments, curtains at the doorways, means supporting said curtains, means securing said curtains comprising sectional edge-retaining strips entered in continuous curtain-retaining grooves in said partitions at opposite sides of the respective doorways, and means for entering said sectional retaining strips in said grooves comprising openings spaced apart a distance equal to the length of the individual retaining strips and of a length at least equal to the space between said individual retaining strips.
50. 16. In a car having partitions disposed longitudinally of the car and spaced apart laterally to define a central aisle, individual compartments upon opposite sides of the aisle, doorways in the partitions to the respective compartments, a pair of curtains at each doorway, means supporting said curtains, means securing said curtains comprising edge-retaining strips entered in curtain-retaining grooves in said partitions at opposite sides of the respective doorways, and means for adjustably and detachably joining said individual pairs of curtains at the respective doorways.
55. 17. In a car having compartments upon opposite sides of a central longitudinal aisle, partitions spaced apart laterally of the car and disposed longitudinally thereof to define said aisle, doorways in the partitions to the respective compartments, curtains supported at the respective doorways, means securing said curtains comprising edge-retaining strips entered in curtain-retaining grooves in said partitions at opposite sides of said doorways, and means for entering said retaining strips in said grooves comprising openings in the respective grooves.
60. 18. In a car having a compartment, partitions defining said compartment, a doorway in one of said partitions, a door for said doorway, curtains supported at the doorway, and means for securing said curtains comprising edge-retaining strips entered in curtain-retaining grooves in the respective doorway.
19. In a car having a compartment, partitions defining said compartment, a doorway in one of said partitions, curtains supported at the doorway, means securing said curtains comprising sectional edge-retaining strips entered in continuous curtain-retaining grooves in said partitions at opposite sides of the doorway, and means for entering said sectional retaining strips in said grooves comprising openings spaced apart a distance equal to the length of the individual retaining strips and of a length at least equal to the space between said individual retaining strips.
20. 20. In a car having a compartment, partitions defining said compartment, a doorway in one of said partitions, a pair of curtains supported at the doorway, means securing said curtains comprising sectional edge-retaining strips entered in continuous curtain-retaining grooves in said partitions at opposite sides of the doorway, means for entering said sectional retaining strips in said grooves comprising openings spaced apart a distance equal to the length of the individual retaining strips and of a length at least equal to the space between said individual retaining strips, and means for detachably joining said pair of curtains at the doorway.

DAVID A. CRAWFORD. 60
ALEXANDER E. MCKINNON.
CARL H. APEL.

CERTIFICATE OF CORRECTION.

Patent No. 2,134,032.

October 25, 1938.

DAVID A. CRAWFORD, ET AL.

It is hereby certified that error appears in the printed specification of the above numbered patent requiring correction as follows: Page 4, second column, line 27, for "place" read plate; page 8, first column, line 48, claim 15, strike out the article "a" second occurrence; same page, second column, line 40, claim 19, after the word "openings" strike out the comma; and that the said Letters Patent should be read with this correction therein that the same may conform to the record of the case in the Patent Office.

Signed and sealed this 6th day of December, A. D. 1938.

Henry Van Arsdale

(Seal)

Acting Commissioner of Patents.
